[21] Appl. No.: 901,740

[57] CLAIM

The ornamental design for a memo card for written messages, substantially as shown and described.

[22] Filed: May 1, 1978

DESCRIPTION

FIG. 1 is a front elevational view of a memo card for written messages showing our new design;

FIG. 2 is an enlarged scale perspective view thereof;
FIG. 3 is an enlarged scale rear perspective view thereof;

FIG. 4 is a left side elevational view thereof; and
FIG. 5 is a cross-sectional view taken along line 5—5 of FIG. 2.
